(57) **CLAIM**

The ornamental design for a microscope, as shown and described.

DESCRIPTION

1. Microscope

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Enlarged

The dash-dash broken lines in the reproductions show portions of the article and form no part of the claimed design. Figures 1.9 and 1.10 show enlarged views of the portions labeled "9" and "10" in Figure 1.1 and Figure 1.11 shows an enlarged view of the portion labeled "11" in Figure 1.2. The dash-dot-dash lines in the reproductions demarcate the boundaries of these enlarged views and form no part of the claimed design.
